TOOTH BRUSH AND POWDER HOLDER

Roscoe J. Byrum, Grand Forks, N. Dak.

Application August 29, 1940, Serial No. 354,774

1 Claim. (Cl. 132—84)

This invention relates to improvements in toilet articles and pertains particularly to an improved combination tooth brush and tooth powder carrier or holder.

The primary object of the present invention is to provide a novelly constructed combined holder and carrier for tooth powder and a tooth brush wherein the brush is kept in a convenient position ready for use, and at the same time is well protected against contamination and against contact with the tooth powder, and wherein a convenient tooth powder receptacle is provided from which the powder may be readily obtained when wanted.

Another object of the invention is to provide a device of the above described character wherein the cover for the brush and for the tooth powder receptacle is common to these units so that by a single movement of removing the cover, the brush and powder are immediately accessible.

A further object of the invention is to provide a combination tooth brush holder and tooth powder receptacle in which a chamber is provided within the powder receptacle in which the handle of the tooth brush is housed, there being a removable cap secured over the end of the receptacle and closing said chamber and providing a cover for the bristle portion or head of the brush and a closure means for the powder discharge opening of the receptacle.

The invention will be best understood from a consideration of the following detailed description taken in connection with the accompanying drawing forming part of this specification, with the understanding, however, that the invention is not to be confined to any strict conformity with the showing of the drawing but may be changed or modified so long as such changes or modifications mark no material departure from the salient features of the invention as expressed in the appended claim.

In the drawing:

Fig. 1 is a view in side elevation of the device embodying the present invention, a portion of the cap of the device being broken away to show the tooth powder discharge opening.

Fig. 2 is a longitudinal sectional view on the line 2—2 of Fig. 1.

Fig. 3 is a transverse sectional view on the line 3—3 of Fig. 2.

Referring now more particularly to the drawing, the numeral 1 generally designates the body of the present device while the single cover or cap which protects and houses the tooth brush head and closes the outlet for the powder re-

ceptacle is indicated generally by the numeral 2. The body portion 1 consists of the cylinder 3, one end of which is closed by the depressed or concave head 4 while the other end is closed by the removable cap 5, which is threadably attached to the end of the cylinder by the screw threaded flange 6. Adjacent the head end of the cylinder 3, a discharge aperture 7 is formed in the wall of the cylinder through which the contents of the cylinder indicated at 8, may be discharged.

Secured in the central part of and opening through the head 4 of the receptacle is a tube 9 which is securely attached to the head 4, as indicated at 10, the tube being open at the end adjacent the head of the receptacle while at its other end it is closed, as indicated at 11, the closed end of the tube being spaced slightly from the removable cover or cap 5.

20 The cap 2 comprises a dome-like body 12, which has a length greater than the length of the head of a tooth brush and which is defined at its base or open position by the surrounding skirt 13. The diameter of the skirt 13 is sufficient to permit the skirt to snugly receive the head end of the cylinder body 3 and the length of the skirt is sufficient for it to cover the discharge opening 7 when the head of the cylinder is inserted into the skirt.

30 The numeral 14 designates a tooth brush, the handle portion of which is indicated at 15, while the bristles are indicated at 16. As shown, the handle 15 of the brush is extended into the tube 9 and the bristles are located above the head 4 and are enclosed within the cap 2 when the latter is frictionally engaged with the end of the cylinder. In this manner it will be at once apparent that the cap 2 performs the double function of enclosing or housing the head of the tooth brush and of closing the tooth powder discharge or outlet opening 7, and thus when the cap is removed the brush can at once be taken out for use and powder discharged from the receptacle onto the brush without having to manipulate any other closure devices.

While the tube 9 has here been shown as being of rectangular cross-section, it will be readily obvious that it may be of circular cross-section if desired and also, while the body 3 has been illustrated as being of circular design, it will be readily obvious that it may be made of polygonal cross-section if found convenient or desirable.

By providing the removable cover 5 for the receptacle 3, the device after being emptied of the tooth powder which it may contain when mar-

keted, can be readily opened for refilling with any powder which the user may desire to thereafter employ.

By forming the top wall 4 concave in the manner illustrated, the insertion of the brush handle into the center receptacle 9 is facilitated and at the same time the brush head is positioned lower down with respect to the receptacle 3, so that the use of a lower or shorter cap 12 is possible.

The numeral 17 designates a body of absorbent material such as cotton or the like, which is placed in the lower end of the handle receiving tube 9 and which may have a few drops of some pleasantly odorous substance placed thereon, such as peppermint or wintergreen. This will give to the brush bristles a pleasant smell and will also function to some extent as an antiseptic.

The cap 2 may be provided with suitable vent holes to permit the proper drying out of the brush bristles by applying a circulation of air through the cap. The container or receptacle 3 together

5 with the tube 9 and the cap 2 may be made of any suitable material, particularly a material which will resist the effects of moisture so that the device may be used indefinitely without rusting or other change.

What is claimed is:

A combined receptacle and tooth brush carrier, comprising an elongated receptacle body having a closure wall at one end having a central opening, a tube having one end in said closure opening and extending into the receptacle, the tube being open at the said one end for the reception of the handle of the tooth brush and having the edge of the wall at the open end swaged over the edge of said opening, the receptacle having a discharge opening in its side wall adjacent the said one end, and a cap formed to receive the said one end of the receptacle to close said discharge opening and to cover the head of a tooth brush which has its handle disposed in said tube.
